UNITED STATES PATENT OFFICE.

RUDOLPH F. STEHLIK, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ROTARY CONNECTER.

Application filed June 29, 1925, Serial No. 40,239. Renewed October 29, 1928.

The present invention relates to improvements in switches of the type known as rotary connecters, and may be considered as an improvement on the connector shown in the 5 application of John E. Ostline, Serial No. 758,998, filed December 31, 1924. Such switches are provided for the purpose of establishing connections to an idle line of a group of lines which are allotted the same 10 number in the directory. The switches used are of the two directional type having ten levels of ten sets of contacts in the level. The contacts in a level may be arranged in one or a plurality of groups, depending 15 upon the size of the groups in question. For night service it is often desirable to plug one or several lines through the attendant's switchboard to individual telephones and for this purpose a special number is allotted in 20 the directory for each telephone, which is different from the number allotted for day service. The number allotted for day service corresponds to that of the first line of the group, while those allotted for night service 25 correspond to successive lines in the group. It is desirable that when the number of the first line is called, if the first line is busy, the switch should automatically rotate and come to rest on the first idle line of a group 30 and further that it should stop when the last line is reached and give the busy signal if all the lines in a group are busy, while if a night number is called, and the latter number is busy, the busy signal is given immediately and no hunting takes place over 35 the remaining lines of the group.

It is the object of the present invention to evolve a rotary connector for bringing about the above results, which is of the same construction as that used when night service 40 facilities are not provided, the only alterations effected being those concerning the circuit arrangements of the switch. According to the present invention this is effected 45 by arranging an automatic rotary control circuit, which is isolated from the private test circuit, and connecting up the contacts wiped over by the rotary control wiper of the switch in three different manners depending 50 upon their position in the group.

In order that the invention may be clearly understood and readily carried into effect, a connector switch in accordance with the invention will now be more fully described,

reference being made to the annexed drawing, which is a diagram of connections of the invention. 55

The switch, being of the two direction type, has the usual vertical and rotary magnets for controlling its selective operation, 60 and also has a release magnet for releasing the switch to normal position. The switch has associated with it the usual ringing current and busy tone sources. The switch shaft carries the usual line wipers and in this 65 case two test wipers—a private and a special wiper. The wipers wipe over the bank contacts of the desired group, the first special wiper contact of which is connected to battery, the last of which is grounded, while 70 the intermediate contacts are left unconnected.

The apparatus having been described more or less in general, a detailed description of the operation of the connector shown in the 75 drawing will now be given. For this purpose, it will be assumed that an automatic subscriber desires to obtain connection with a subscriber in a private branch exchange served by a group of trunk lines. The customary subscriber's substation, individual line switch, and selector switches as used by an automatic subscriber in completing a connection are not shown but are well understood by those skilled in the art and form 80 no part of the present invention. It will therefore suffice to say that in response to the removal of the receiver by the calling subscriber, his individual line switch seizes an idle trunk line leading to an idle selector 85 switch, and in response to the operations of the subscriber's calling device, the selector switches are operated to select an idle trunk line leading to a connector switch. 90

Let us assume that the calling subscriber 95 has established his connection as far as the last selector, and that the selector has come to rest on bank contacts connected to the conductors 20, 21, and 22 of the connector switch shown in the drawing, this being the 100 first idle connector accessible to the said selector. When the selector switch comes to rest upon the contacts associated with conductors 20, 21, and 22, the switching relay of the selector completes an energizing circuit 105 for the line relay 4 of the connector switch as follows: from ground by way of the lower winding of line relay 4, normally closed

springs controlled by armature 31 of relay 3, conductor 21, over the intervening switches and the subscriber's loop back to conductor 20, normally closed springs controlled by 5 armature 30, and through the upper winding of line relay 4 to battery. Relay 4 at armature 33 and its working contact completes an energizing circuit for the slow to release relay 5. Relay 5, upon energizing, connects 10 ground to the release trunk conductor 22 at armature 34 and its working contact. This ground completes a holding circuit for the switches preceding the connector switch for maintaining said switches in an operated position, and in addition, maintains the trunk 15 line leading to the connector busy to all other selectors having access thereto. Furthermore, relay 5, at armature 36 and its working contact, prepares a circuit for the vertical magnet 15 and at its resting contact opens a point in the release circuit; and at armature 35 and its working contact grounds the holding conductor 65.

The calling subscriber may now manipulate his calling device in accordance with 25 the remaining digits in the number of the private branch exchange, which in this case are assumed to be 1 and 1. In response to the next operation of the calling device by 30 the calling subscriber, the circuit of the line relay 4 is interrupted in known manner and the relay therefore deenergizes for a short interval. A circuit may now be traced for the vertical magnet 15 as follows: from 35 ground by way of armature 33 and its resting contact, armature 36 and its working contact, normally closed contact and off-normal spring 62, slow to release series relay 6, and vertical magnet 15 to battery. The vertical 40 magnet 15 and relay 6 energize in series and by the operation of the vertical magnet 15, the shaft and wipers are raised until the wipers 70 to 73, inclusive, are opposite the first level. Relay 6 maintains its own circuit 45 and that of the vertical magnet intact after the shifting of the off-normal springs which takes place on the first vertical step. After the first impulse, since there is only one in this case, the line relay 4 energizes again and 50 opens the circuit for relay 6 and vertical magnet 15 at armature 33. Relay 6, upon deenergizing after a short interval, transfers the impulsing circuit from the vertical magnet to the rotary magnet at armature 37.

Upon the dialling of the final digit of the called subscriber's number, in this case the digit 1, the circuit of relay 4 is again interrupted. The line relay 4, upon deenergizing, completes parallel circuits for the rotary magnet 16 and relay 11 as follows: from ground, armature 33 and its resting contact, armature 36 and its working contact, normally open contacts controlled by off-normal spring 62, armature 37 and its resting contact, resting contact and armature 49, and through relay 11 to battery, and also continuing by way of armature 57 and its resting contact, resting contact and armature 42, through rotary magnet 16 to battery. The rotary magnet 16 and relay 11 energize in parallel. The rotary magnet 16 steps the wipers 70-73, inclusive, into engagement with the bank contacts 74-77, inclusive, of the first trunk in the first level. Relay 11, upon energizing, at armature 53 and its working contact shunts armature 49; at armature 52 and its resting contact opens the circuit of the switching relay 12; at the working contact of the same armature prepares a circuit for test relay 10; and at armature 54 prepares a circuit for relay 9. It may be stated now that since the first set of bank contacts in the first level are those of the first line of the group, the bank contact 75 will have battery connected thereto. Furthermore, let it be assumed that the first line of the group is busy, that is, the bank contact 74 is grounded by the test wiper of another connector. The ground on bank contact 74 energizes test relay 10 by way of wiper 70, normally closed contacts controlled by armature 44, armature 43 and its resting contact, armature 52 and its working contact, resting contact and armature 58, normally closed contacts controlled by armature 45, normally closed contacts controlled by armature 43, resting contact and armature 60, and test relay 10 to battery. Relay 10, upon energizing, at armature 49 opens a point in the rotary impulsing circuit, at armature 48 prepares a lock-circuit for itself, at armature 51 connects the busy machine, and at armature 50 closes a circuit for relay 9 which may be traced from grounded holding conductor 65, upper winding of relay 9, armature 50 and its working contact, working contact and armature 54, wiper 71, and bank contact 75 to battery. Relay 9, upon energizing, at armature 47 prepares a locking circuit for itself; at armature 44 closes a new holding circuit for relay 10 before the original operating circuit opens; at armature 66 opens the circuit of the busy signal; and at armature 45 prepares an energizing circuit for stepping relay 8. A short interval after the rotary impulse is terminated the slow to release relay 11 deenergizes and at 115 normally closed contacts controlled by armature 54 a locking circuit is closed for relay 9 which may be traced from grounded holding conductor 65, upper winding of relay 9, armature 50 and its working contact, normally closed contacts controlled by armature 54, working contact and armature 47, and lower winding of relay 9 to battery. This locking circuit is closed before the original operating circuit opens due to the make before break contacts controlled by the circuit closing armature. It will be ob-

ture 49, and through relay 11 to battery, and also continuing by way of armature 57 and its resting contact, resting contact and armature 42, through rotary magnet 16 to battery. The rotary magnet 16 and relay 11 energize in parallel. The rotary magnet 16 steps the wipers 70-73, inclusive, into engagement with the bank contacts 74-77, inclusive, of the first trunk in the first level. Relay 11, upon energizing, at armature 53 and its working contact shunts armature 49; at armature 52 and its resting contact opens the circuit of the switching relay 12; at the working contact of the same armature prepares a circuit for test relay 10; and at armature 54 prepares a circuit for relay 9. It may be stated now that since the first set of bank contacts in the first level are those of the first line of the group, the bank contact 75 will have battery connected thereto. Furthermore, let it be assumed that the first line of the group is busy, that is, the bank contact 74 is grounded by the test wiper of another connector. The ground on bank contact 74 energizes test relay 10 by way of wiper 70, normally closed contacts controlled by armature 44, armature 43 and its resting contact, armature 52 and its working contact, resting contact and armature 58, normally closed contacts controlled by armature 45, normally closed contacts controlled by armature 43, resting contact and armature 60, and test relay 10 to battery. Relay 10, upon energizing, at armature 49 opens a point in the rotary impulsing circuit, at armature 48 prepares a lock-circuit for itself, at armature 51 connects the busy machine, and at armature 50 closes a circuit for relay 9 which may be traced from grounded holding conductor 65, upper winding of relay 9, armature 50 and its working contact, working contact and armature 54, wiper 71, and bank contact 75 to battery. Relay 9, upon energizing, at armature 47 prepares a locking circuit for itself; at armature 44 closes a new holding circuit for relay 10 before the original operating circuit opens; at armature 66 opens the circuit of the busy signal; and at armature 45 prepares an energizing circuit for stepping relay 8. A short interval after the rotary impulse is terminated the slow to release relay 11 deenergizes and at normally closed contacts controlled by armature 54 a locking circuit is closed for relay 9 which may be traced from grounded holding conductor 65, upper winding of relay 9, armature 50 and its working contact, normally closed contacts controlled by armature 54, working contact and armature 47, and lower winding of relay 9 to battery. This locking circuit is closed before the original operating circuit opens due to the make before break contacts controlled by the circuit closing armature. It will be ob-

served from this locking circuit that the windings of relay 9 oppose each other, however, the ampere turns of the upper winding being far in excess of the lower winding, the upper winding continues to receive sufficient current to hold the relay in operated position. As a further result of the deenergization of relay 11, armature 52 closes a circuit for relay 8, which may be traced from grounded release trunk conductor 22, armature 48 and its working contact, normally closed contacts controlled by armature 52, resting contact and armature 58, working contact and armature 45, resting contact and armature 64, and relay 8 to battery. Relay 8, upon energizing, completes at armature 41 a locking circuit for itself; and at armature 42 closes a circuit for rotary magnet 16, which may be traced from ground on the release trunk conductor 22, working contact and armature 42, and rotary magnet 16 to battery. Rotary magnet 16, upon energizing, advances the wipers 70-73, inclusive, into engagement with the next set of bank contacts which, as will be seen from the drawing, has its contact 78 free from battery or ground potential. Rotary magnet 16, at its interrupter contact 64, opens the circuit of stepping relay 8 and the latter falls back and opens the circuit of the rotary magnet at armature 42, as well as opening its own locking circuit at armature 41. If the test contact of the next trunk is free relay 10 will be deenergized to prevent stepping relay 8 from energizing and stepping the switch further as will be explained hereinafter in connection with the last trunk in the group being idle. If the second trunk is busy its test contact will be grounded and relay 10 will be held energized. Relay 8 will again become energized over a circuit previously traced, whereupon the rotary magnet 16 will again energize to rotate the wipers into contact with third trunk. This alternate operation of relay 8 and rotary magnet 16 continues until an idle trunk is found or until the last trunk in the group is reached. The last trunk of each group has its lower contact such as 79 grounded, and if the last trunk is busy the contact engaged by wiper 70 will also be grounded. When wiper 71 comes to rest upon contact 79, which is grounded, relay 9 will no longer hold energized due to this ground being connected at a junction point in the previously traced locking circuit of relay 9, between its two windings, thus shunting out the upper winding and establishing a direct circuit for the lower winding to ground at contact 79 by way of armature 46 and its working contact. With the upper winding shunted out the differentially wound relay is energized solely by its lower winding, which reverses the polarity of the relay coil and causes the relay to quickly deenergize and unlock. Relay 9, upon deenergizing at armature 46 opens its locking circuit; at armature 45 prevents the stepping relay 8 from re-energizing; and at armature 44 opens the locking circuit of relay 10 by way of wiper 70. However, on account of relay 8 being deenergized at this time a locking circuit for relay 10 is closed by normally closed make-before-break contacts controlled by armature 45, which may be traced from grounded release trunk conductor 22, armature 48 and its working contact, normally closed contacts controlled by armature 52, resting contact and armature 58, normally closed contacts controlled by armature 45, normally closed contacts controlled by armature 43, resting contact and armature 60, and relay 10 to battery. Should relay 9 deenergize before relay 8 deenergizes a locking circuit is still maintained for busy relay 10 due to the make-before-break contacts controlled by armature 43 of relay 8. As a further result of the deenergization of relay 9, the circuit including the busy machine is closed at armature 66, thus giving the calling party the usual busy signal.

The calling party upon hearing the busy signal will replace his receiver upon the switchhook whereupon line relay 4 will deenergize and open the circuit of slow to release relay 5 at armature 33. Slow to release relay 5 upon deenergizing disconnects ground from the holding conductor 65 at armature 35 and also disconnects ground from the release trunk conductor 22 at armature 34, whereupon relay 10 deenergizes and the preceding switches are released in known manner. As a further result of the deenergization of relay 5, armature 36 completes the following circuit for release magnet 14; from ground, armature 33 and its resting contact, armature 36 and its resting contact, off-normal spring 13 and its working contact, and release magnet 14 to battery. By the operation of the release magnet the switch shaft and wipers 70 to 73, inclusive, are restored to normal whereupon the off-normal springs 13 and 62 are shifted, thus opening the circuit of the release magnet 14 which thereupon deenergizes.

Returning now to the operation of the connector when it established connection with the last line of a group, we will assume that this line was idle and give a detailed description of the operation of the connector under these circumstances. If the last line of the group is idle no ground potential will be encountered by test wiper 70 and busy relay 10 will deenergize, thus disconnecting the busy tone machine. Relay 9 will deenergize due to ground being encountered on the last lower contact as already explained. Battery potential through the cutoff relay and rotary magnet of the wanted subscrib-

er's line switch (not shown) will now be encountered by test wiper 70, and the following circuit will be completed for switching relay 12, battery through the rotary magnet 5 and cutoff relay of the line switch of the wanted line to test wiper 70, the normally closed resting contact controlled by armature 44, armature 43 and its resting contact, armature 52 and its resting contact, upper 10 winding of relay 12, resting contact and armature 48, to ground on the release trunk conductor 22. Switching relay 12 and the line switch cut-off relay energize in series over the above traced circuit. The cut-off relay 15 energizes slightly before the switching relay 12 owing to the core of the latter relay being provided with a copper collar at its armature end. This is done to insure that the cut-off relay will have disconnected the normal 20 battery and ground connections from the called line before the switching relay connects ringing current thereto. Switching relay 12, upon energizing, completes at armature 59 a locking circuit for itself to ground at the holding conductor 65; at armature 60 opens a point in the circuit of 25 busy relay 10; at armature 56 grounds the test wiper 70; at armatures 55 and 61 connects interrupted ringing current from the 30 ringing machine GEN. to the line wiper 73. The calling subscriber is given the well known ringing tone, when ringing current is applied to the wanted line, through the small 35 capacity condenser 80, which is connected across armature 38 and its working contact.

The wanted subscriber upon removing his receiver in response to the ringing of his bell, completes the following circuit for the 40 ring cut-off relay 7; grounded generator or grounded contact at armature 63, resting contact and armature 40, armature 61 and its working contact, wiper 73, over the wanted party's loop to wiper 72, working contact and armature 55, armature 38 and its resting contact and the upper winding of 45 relay 7 to battery. The ring cut-off relay 7 energizes over the above traced circuit and completes a locking circuit for itself at armature 39, and at armatures 38 and 40 breaks the ringing current and completes the talking 50 circuit between the calling and called subscribers. In addition, relay 7 completes a circuit for the back bridge relay 3 as follows; from ground, lower winding of said 55 relay by way of working contact and armature 40, armature 61 and its working contact, wiper 73 over the called party's loop to wiper 72, working contact and armature 55, armature 38 and its working contact, to upper winding of said relay and battery. The back bridge relay, upon energizing, 60 reverses the flow of current to the calling subscriber at armatures 30 and 31. After the 65 conversation has been completed the release

of the connection takes place in the hereinbefore described manner upon the calling party replacing his receiver upon the switchhook, with the difference that relay 10 is now already deenergized while the switching relay 12 and ringing relay 7 are deenergized when ground is removed from the holding conductor 65.

A brief description will now be given of the operation which takes place when a 75 number corresponding to an intermediate trunk of a group is dialled. Referring to the initial energizing circuit of stepping relay 8, it will be seen that this relay can only be energized through being connected 80 to ground on the release trunk by way of relays 9 and 10 being energized and relay 11 being deenergized. Further, since relay 9 cannot energize except with the test wipers standing on the first trunk and as a result of the energization of relay 10, it will be assumed that the first trunk is found busy when the wipers reach the contacts of that trunk. Relays 10 and 9 will energize as already explained, but relay 9 cannot now lock 90 up due to relay 11 remaining energized during rotation, and will deenergize along with relay 10 as soon as the test wipers step off of the first trunk contacts. Relay 10 may, or may not, reenergize upon reaching the 95 next trunk contacts depending upon whether the trunk is busy or not, but is of no consequence at this time. Relay 9, however, cannot reenergize after passing the first trunk until after the switch is released and set 100 over again. Relay 8, therefore, cannot energize under these circumstances and since this relay controls the circuit for rotary magnet 16, no hunting will take place. This feature is of great practical use as it enables 105 any line of a group except the first to be listed in the directory for night service.

Having described the invention, what is considered to be new and desired to have protected by Letters Patent will be pointed out in the appended claims.

What is claimed is:

1. In a telephone system, a rotary connector switch, a group of lines accessible to said switch, each line having a regular and a special test contact, a cut-off relay connected to each regular test contact, and different poles of a battery permanently connected respectively to the first and last of said special test contacts.

2. In a telephone system, a rotary connector switch, a group of lines accessible to said switch, each line having a regular and a special test contact, said contacts being unconnected with each other, a cut-off relay connected to each regular test contact, and a battery having one pole connected to the first of said special test contacts and the other pole connected to the last of said special test contacts.

3. In a telephone system, a rotary connector switch, a group of lines accessible to said switch, each line having a regular and a special test contact, a cut-off relay connected to each regular test contact, a resistance, and a battery having one pole connected to the first of said special test contacts through said resistance and the other pole connected direct to the last of said special test contacts.

4. In a telephone system, a rotary connector switch, a group of lines accessible to said switch, each line having a regular and a special test contact, a cut-off relay connected to each regular test contact, and a battery having one pole normally connected to the first of said special test contacts and the other pole normally connected to the last of said special test contacts, means for directly operating said switch to select any line of said group, and means in said switch controlled from the test contacts of the selected line and effective to cause the switch to hunt an idle line only in case the selected line is the first line of the group.

5. In a telephone system, a rotary connector switch, a group of lines accessible to said switch, each line having a regular and a special test contact, said contacts being unconnected with each other, a cut-off relay connected to each regular test contact, and a battery having one pole connected to the first of said special test contacts and the other pole connected to the last of said special contacts, means for directly operating said switch to select any line of said group, and means in said switch controlled from the test contacts of the selected line for preventing any hunting action of the switch unless the selected line is the first line of the group.

6. In a telephone system, a switch having two test wipers, a group of lines, each line having test contacts accessible to said wipers, means for operating said switch to select the first line of said group, automatic means controlled over both said wipers for starting said switch rotating in search of an idle line if the first line is found busy, automatic means controlled over one of said test wipers alone for continuing the hunting movement if the intermediate lines are found busy, and automatic means controlled over the other said test wiper for stopping the hunting movement when the last line is reached whether the last line is busy or idle.

7. In a telephone system, a switch having two test wipers and a group of regular and special test bank contacts, automatic means controlled over both said wipers for starting said switch rotating in search of an idle regular contact when the first regular contact is found busy, automatic means controlled over one of said test wipers for continuing the hunting movement when the intermediate

regular contacts are found busy, and automatic means controlled over the other of said test wipers for stopping the hunting movement when the last special contact is reached regardless of whether the last regular contact is busy or idle.

8. In a telephone system, a switch having two test wipers and two sets of bank contacts, a test relay, a rotary series relay, means including the energization of said series relay for connecting said test relay to the first of one set of said contacts over one wiper, means responsive to said connection for energizing said test relay when said contact is busy, a third relay, means including the energization of said test and series relays for connecting said third relay to the first of the other set of said contacts over the other wiper, and means responsive to the energization of said third relay and the de-energization of said series relay for operating said switch in an automatic hunting movement.

9. In a telephone system, a switch, groups of lines terminating in said switch, each group including more than two lines, means for directly operating said switch to select any line in any group, means effective only in case the first line in a group is selected for causing the switch to hunt for an idle line, a set of test contacts for each line comprising a regular and a special test contact, and suitable circuit connections to the first and the last of said special test contacts for permanently connecting different poles of battery thereto for controlling the hunting operation of the switch.

10. In a telephone system, a switch, a test contact accessible to said switch and having one pole of a battery permanently connected thereto, a second test contact accessible to said switch and having the other pole of said battery connected thereto, means for operating said switch to select said first contact, means operated responsive such selection by current from said battery for causing said switch to start a hunting movement, and means operated by current from said battery in case the switch selects said second contact in its hunting movement for stopping such hunting movement.

11. In a telephone system, a switch, a group of lines, a special test contact for each line of said group, the special test contact of the first line in the group being permanently connected to the ungrounded pole of battery and the special test contact of the last line in the group permanently connected to the grounded pole of battery, means for directly operating said switch to select the terminal of the first line in the group, means responsive to the battery potential on said first terminal and operative in case the first line is busy for causing said switch to automatically hunt for an idle line in said

- group, and means for stopping the hunting movement of the switch when the grounded last terminal is engaged regardless of whether the last line is busy or idle.
- 5 12. In a telephone system, a group of lines, a switch having a special test wiper, a special test contact for each line of said group accessible to said wiper, the last of said special test contacts being permanently connected to grounded pole of battery, means for operating said switch to hunt for an idle line in said group, and means operative responsive to the engagement of said wiper with said grounded test contact for stopping 10 the hunting movement.
13. In a telephone system, a rotary connector switch, a group of lines accessible to said switch, each line having a special test contact, and permanent connections from the 20 first and last of said special contacts to opposite poles of the exchange battery.
14. In a telephone system, a switch having a directive movement and an automatic hunting movement, two test wipers in said switch 25 and contacts engaged thereby responsive to the directive movement of said switch, a test relay in said switch energized over a circuit including one wiper, another relay in said switch energized over a circuit closed by said 30 test relay through the other wiper but excluding the first wiper to start the hunting movement, and means for deenergizing said other relay over a circuit including said other wiper to stop the hunting movement.
15. In a telephone system, a group of lines, a switch having two test wipers, a set of bank contacts for each line accessible to said wipers, a test relay, a rotary series relay, means including the energization of said 40 series relay for connecting said test relay to one of the contacts of the first set over one wiper, means responsive to said connection for energizing said test relay when said contact is busy, a third relay, means including the other contact of the first set, the other wiper and contacts on the test and series
- relays for closing an energizing circuit for said third relay, means responsive to the energization of said third relay and the deenergization of said series relay for operating said switch in an automatic hunting movement, and means responsive to the engagement of said other wiper with one of the contacts of the last set for deenergizing 50 said third relay to stop the hunting movement.
16. In a switch having an automatic hunting movement, a differential relay having two windings, means for energizing said relay over its first winding to cause said switch to start its hunting movement, said relay closing a holding circuit for itself including both windings, the first winding having the greatest magnetizing effect, and means for shunting the first winding and for increasing 60 the current flow in the second winding to cause said relay to deenergize to stop the hunting movement of said switch.
17. In a telephone system, a relay having two windings, means for energizing said relay over its first winding, contacts on said relay closed responsive to said energization for closing a locking circuit for said relay, said locking circuit including both windings of said relay in series, the current flow in 70 said windings being in opposite direction and the second winding being less powerful than the first, and means for shunting the first winding and for increasing the current flow in the second winding to cause said 75 relay to deenergize to open said locking circuit.
18. In a rotary connector, a relay, means including a test wiper of said switch for energizing said relay to start the hunting movement, and means including said test wiper for reversing the polarity of the relay magnet, whereupon said relay is deenergized to stop the hunting movement.

In witness whereof, I hereunto subscribe my name this 25th day of June, A. D., 1925.

RUDOLPH F. STEHLIK.
